CONTAINER FOR HYPODERMIC NEEDLES

Seymour N. Blackman, Teaneck, N. J.

Application March 19, 1952, Serial No. 277,494

5 Claims. (Cl. 206—43)

1

This invention relates to a container for hypodermic needles.

It is an object of my invention to provide a container of the character described which houses a plurality of needles in such fashion that although the needles are located close to one another in order to conserve space, they are so relatively arranged that any one of them can be removed easily.

It is a more specific object of my invention to provide a container of the character described in which a large number of needles are located close to one another in substantially a common plane but are automatically separated into two groups when the container is opened so as to render the needles more accessible.

Other objects of my invention will in part be obvious and in part will be pointed out hereinafter.

My invention accordingly consists in the features of construction, combination of elements and arrangement of parts which will be exemplified in the device hereinafter described and of which the scope of application will be indicated in the appended claims.

In the accompanying drawings in which is shown one of the various possible embodiments of my invention,

Fig. 1 is a plan view of a closed container constructed in accordance with the present invention;

Fig. 2 is a similar view of the container open;

Fig. 3 is an enlarged sectional view taken substantially along the line 3—3 of Fig. 1;

Fig. 4 is a fragmentary sectional view taken substantially along the line 4—4 of Fig. 3; and

Fig. 5 is a view similar to Fig. 4 but with the needles removed.

Referring now in detail to the drawings, the reference numeral 10 denotes a needle container constituting a shallow box comprising a tray 12 to the rear edge of which a lid 14 is rotatably secured as by hinges 16. A catch 18 is provided to hold the lid closed against accidental opening. Both the tray and lid are of substantially the same slight depth, a little less than the thickness of the hub 20 of a hypodermic needle 22 in the container.

The container may be fabricated from any suitable material such for instance as metal. However, I prefer to use a synthetic plastic, both for the sake of appearance and to enable the container to be employed in practicing the invention shown, described and claimed in my co-pending application for a Container for Hypodermic

2

Needles, Serial No. 277,493, filed March 19, 1952. To this end the lid 14 desirably is made from a clear transparent thermoplastic and the tray from an opaque thermoplastic.

5 The lid includes means to hold a group of hypodermic needles in given positions within the container and the tray includes a similar means for holding another group of such needles in like manner. Said means may be of any suitable construction, for example, the tray may be provided with a plurality of pairs of clips 23, each of which is formed in one piece with the tray, for example, molded therewith. The clips are resilient and the two legs of each pair of clips are bowed outwardly away from one another. The free edges of each pair of legs are closer together and further from the wall of the tray than the maximum width of a hub so that when the hub is forced between the legs they will spread and thereafter snap back to frictionally engage the hub whereby to hold a hypodermic needle in predetermined position in the container.

10 The needle-holding means of the lid desirably is identical in construction with the needle-holding means of the tray.

15 Each said needle-holding means supports a needle with the cannula parallel to and slightly spaced from the plane of the parting line 24 between the lid and the tray and parallel to the axis of rotation of the hinge.

20 All the needle-holding means of the tray are aligned, that is to say, all the pairs of clips in the tray are arranged in a row perpendicular to the axis of rotation of the hinge whereby the hubs of all the needles carried by the tray are aligned. Likewise the hubs of all the needles carried by the lid are aligned.

25 In pursuance of my invention the needles supported by the tray have their hubs located adjacent one side of the container and the needles supported by the lid have their hubs located adjacent the opposite side of the container. In other words, the hubs carried by the lid are adjacent one side of the container and the cannulae

30 associated with said hubs point towards the opposite side of the container. The hubs carried by the tray are located adjacent said opposite side of the container and the cannulae associated with the hubs point towards the first set of hubs. The tips of the cannulae of each group are approximately registered with the rims of the hubs of the other group (see Fig. 1). The hubs of the needles in each group are spaced apart slightly and the two groups of needles are so oriented 35 with respect to one another that each cannula

of one group is located between a pair of cannulae of the other group when the container is closed. Moreover, the needles are so supported with respect to the walls of the tray and lid that when the container is closed all the cannulae lie almost in the plane of the parting line as best shown in Figs. 3 and 4. Thus, when the container is open, as illustrated in Fig. 2, the two groups of needles are widely spaced apart and any needle in either group may be readily picked up by hand or instrument. However, when the container is closed as shown in Fig. 1, the two groups of needles are sandwiched so as to take up a minimum of space while still presenting a neat and pleasant appearance.

It thus will be seen that I have provided a device which achieves all the objects of my invention and is well adapted to meet the conditions of practical use.

As various possible embodiments might be made of the above invention, and as various changes might be made in the embodiment above set forth, it is to be understood that all matter herein described, or shown in the accompanying drawings, is to be interpreted as illustrative and not in a limiting sense.

Having thus described my invention, I claim as new and desire to secure by Letters Patent:

1. A container for hypodermic needles including a receptacle comprising a shallow tray, a shallow lid, and means hingedly joining said lid and tray, means carried by said lid for individually detachably holding each needle of a group of hypodermic needles; means carried by the tray for individually detachably holding each needle of a group of hypodermic needles, the needles of both groups being located in substantially a common plane and each pair of adjacent needles of either group having a needle of the other group

located between them when the container is closed.

2. A container as set forth in claim 1 wherein needles of each group point in opposite directions.

3. A container as set forth in claim 1 wherein needles of each group point in opposite directions and the tips of the needles of one group are aligned with the hubs of the needles in the other group.

4. A container as set forth in claim 1 wherein the hubs of the needles of each group are aligned, the hubs of one group being located adjacent one side of the receptacle and the hubs of the other group being located adjacent the opposite side of the receptacle.

5. A container for hypodermic needles including a receptacle comprising a shallow tray, a shallow lid, and means hingedly joining said lid and tray, means carried by said lid for individually detachably holding the hubs of a group of hypodermic needles, and means carried by the tray for individually detachably holding the hubs of the needles of a second group of hypodermic needles, said holding means being located to dispose a needle of either group between a pair of needles of the other group when the container is closed.

SEYMOUR N. BLACKMAN.
